UNITED STATES PATENT OFFICE.

ARVID H. NERO, OF WEST HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed February 15, 1926. Serial No. 88,310.

My invention relates to electric switches and particularly to a switch of the reciprocating cam slide type. The object of my invention is to provide a mechanism having certain features of improvement over that disclosed in my copending application Ser. No. 27,298, filed May 1, 1925.

In the accompanying drawings—

Fig. 1 is a vertical section on the line 1—1, Fig. 2, through an electric switch in which my invention is embodied in one form;

Fig. 2 is a section on the line 2—2, Fig. 1;

Fig. 3 is a plan view of the mechanism; 15 and

Fig. 4 is a perspective of the switch bar detached.

In the construction shown in my copending application above mentioned, the reciprocating cam slide of the switch mechanism is struck from sheet metal, and the operating member comprises a composite lever, the finger grip portion of which is of insulating material. The latter is of expensive construction, and is, moreover, out of harmony with the fitting casing when the latter is formed of metal. According to the present invention the operating lever is of metal throughout, while the cam slide is formed from insulating material, such as sheet fiber. Various other features of improvement in detail of construction will be hereinafter referred to.

While I have shown my invention embodied in the switch mechanism for a lamp socket, it will be recognized that it is applicable to various other types of electrical fittings, and is in no sense restricted to a lamp socket. In the form here shown the switch comprises an insulating base block 15, and a cover disc 16 of insulating material, such as fiber, or the like, which overlies one end of the block 15 and closes the switch chamber 17. Guideways 18 and 19 are formed in the block 15 transversely thereof, and the cam slide 20 works therein across the switch chamber.

The slide 20 is preferably cut from sheet fiber or other insulating material, and one edge is shaped intermediate its ends to form a peaked cam 21, which traverses the switch chamber 17 on the reciprocation of the slide.

At one end 22 the slide is of a width substantially corresponding to the depth of the guide channel 18, and the opposite margins

of this end are preferably rounded to reduce friction. Adjacent its opposite end the edge of the slide opposite that in which the cam 21 is formed, is recessed to form an open notch 23 adapted for engagement by the bell crank arm 24 of an operating lever 25. The latter is struck from sheet metal and the arm 24 is connected to the shank of the lever by a U-bend 26. At the crest of the U-bend are laterally extending lugs 27 which take into recesses 28 and 29 on opposite sides of the guide slot 19. The lugs 27 are confined in these recesses by the cover disc 16, so that the lever is freely pivoted and rocks on the lugs 27 as trunnions, with the arm 24 working in the guide slot 19.

On opposite sides of the guide slot 18 and lying against the adjacent wall of the switch chamber 17 are the switch contacts 30 and 31. The contact 30 is integral with the wire terminal 32, while the contact 31 is integral with the center contact 33 of the socket.

Straddling the cam slide 20 is a floating Y-shaped switch bar 34, the legs of which span the contacts 30 and 31 in circuit-closing position. The switch bar is thrust against the cam 21 of the slide by a coil spring 35 seated in a well 36 opening to the bottom of the switch chamber. To reduce the frictional engagement between the switch bar and the cam 21, and to take the wear between these parts, I provide a saddle piece 37 loosely resting on the crotch of the switch bar and bearing against the cam surface of the slide. The curved bearing surface of the saddle reduces friction and maintains smooth the engaging face of the cam. This is a feature of practical importance since the switch bar 34 is struck from sheet metal, and the engagement of its edges with the face of the fiber cam 21 would otherwise tend to roughen the surface of the latter and not only make the action of the switch more difficult, but even endanger its proper operation. It will be noted that the spring 35 thrusts the slide toward the cover disc 16. The wide end 22 of the slide prevents substantial displacement thereof by the spring.

At its other end, the operating lever limits the displacement of the slide under the effort of the spring, and the trunnions 27, or U-bend 26, bear against the cover disc 16. The slide has limited freedom of play therefore at this end, against the effort of the spring, and moves toward and away from

the bottom of the guide slot 19 as the lever end swings through its arc.

The operation of the switch is readily understood. In the position shown in Fig. 1, the circuit is closed by the switch bar 34, the legs of which engage the fixed contacts 30 and 31. Upon depression of the free end of the lever 25 the arm 24 thereof, which engages the notch 23 of the slide 20, shifts the latter across the switch chamber 26. Inasmuch as the switch bar 34 is held against movement in the same direction by its engagement with the contacts 30 and 31, the cam displaces the switch bar against the effort of the spring 35. When the crest of the cam 21 passes the plane of the switch bar the stress of the spring causes the switch bar to ride the opposite incline of the cam and thus throw across the switch chamber 17 to open-circuit position. The operation of the mechanism is reversed when the free end of the switch lever 25 is restored to its initial position.

The parts of the mechanism are all readily struck from sheet material, and when used with a socket, as in the present instance, the entire mechanism, as well as the socket contacts are maintained in position by the two screws 38 and 39 which pass through the block 15 and take into the yoke 40 which overlies the base flange of the screw shell contact 41, and is itself integral with the wire terminal 42.

Various modifications in detail will readily occur to those dealing with the problem, without departing from what I claim as my invention.

I claim—

1. In an electric switch, an insulating body

recessed to form a switch chamber, and a guideway opening therefrom, a cooperating insulating cover forming a wall of the guideway, a cam slide working in said guideway, and a switch bar acted on by the cam slide, in combination with a spring pressing the switch bar against the cam slide and urging said slide toward said cover, together with a pivoted operating lever engaging the slide and limiting the displacement of the latter toward said cover under the effort of said spring.

2. In an electric switch, a forked sheet metal switch bar, a saddle piece at the crotch of the switch bar, together with a slide of insulating material having a peaked cam bearing against said saddle.

3. In an electric switch, a forked sheet metal switch bar, a saddle freely seated at the crotch of the switch bar, together with a slide having a peaked cam bearing against said saddle, the latter presenting a rounded face to the cam.

4. In an electric switch, a cam slide, and a switch bar acted on by the cam slide, in combination with a pivoted lever for reciprocating the latter, and a spring pressing the switch bar against the cam slide and thrusting the slide toward the lever.

5. In an electric switch, a cam slide having play in a direction normal to its length, a pivoted lever for reciprocating the slide, a switch bar riding the cam slide, and a spring urging the switch bar and slide toward the operating lever.

In testimony whereof I have signed my name to his specification.

ARVID H. NERO.
